SCREEN

Richard E. Mason, New York, N. Y.

Application March 4, 1940, Serial No. 322,127

7 Claims. (Cl. 156—14)

This invention relates to screens and similar devices used in windows, ventilating systems, and other places where effective sealing and convenience of installation and removal are important. The principal object of the invention is to produce a unitary screen of sufficient inherent flexibility and compressibility so that it can be readily installed or removed, and while in place will effectively seal any cracks around the edges, so that the screen may function with maximum effectiveness. Other objects are to make a screen which will not warp or corrode, and one which will adapt itself to the variations ordinarily found in window casings. Window casings are usually made of wood, which swells and shrinks with the weather. It sometimes happens that screens are fitted correctly when first installed, but later become so tight that they cannot be removed, due to the swelling or shrinking of the wood. The present invention overcomes that difficulty. Various other objects will become apparent as the description proceeds.

Referring now to the drawing, which illustrates by way of example three forms of the screen,

Fig. 1 shows a screen with flexible cushions at the ends or sides.

Fig. 2 is a modified form with the cushions or flexible material on all four sides, that is, the top and bottom as well as the sides.

Fig. 3 illustrates a somewhat different form, with more reenforcement at the screen border and narrower cushioning at the edge, giving the tip greater flexibility.

Similar reference numerals refer to similar parts throughout the various views.

Referring now to Fig. 1, the screen 1 of any suitable wire mesh is mounted in a frame 2, of wood, plastic, metal, or other suitable material, preferably having a slight flexibility. Attached to the screen frame 2 at its two sides are wings or cushions 3 and 3' of soft, flexible, resilient material, of sufficient depth and body so that it can readily be compressed a half inch or more on each side and still have sufficient resiliency to spring back again with considerable force and rigidity. This body of resilient material permits the screen to be installed in the grooves of a window casing or other frame by merely pushing it in place by hand, the resilient material 3 yielding enough to pass over the edge of the groove and then expanding into the groove so as to fit snugly in place. The material 3 has sufficient body to hold firmly enough against ordinary forces, such as wind; and yet when it becomes necessary to remove the screen, it can be pushed

out by hand without special tools or effort, even if the frame has shrunk or swelled in the meantime.

I have found soft rubber, sponge rubber, and the various artificial substitutes for the same, excellent materials for the cushions 3. In some cases it may be desirable to provide one or more holes 4—4, of any desired shape, to increase the flexibility of the cushions, particularly when they are made of the tougher or less spongy grades of rubber or rubber substitutes.

One of the difficulties with removable screens is that many window casings are not true and square, and that the bottom of the sash may not be parallel with the bottom of the window casing, or may have irregular defects. The modification shown in Fig. 2 is preferable in such instances.

Referring now to Fig. 2, the screen mesh 1 has its frame 2 surrounded on all four sides with cushion material 3' and 3'', such as sponge rubber, soft rubber, rubber substitutes, or equivalent material. The cushions 3' at the top and bottom need not be as deep as the wings or cushions 3'' at the sides. The top and bottom cushions 3' take care of irregularities in the sash and window casing, effectively sealing them, while the side cushions 3'' which seal the remainder also have the function as previously described of bending and compressing when the screen is inserted or removed from the window frame, to facilitate installation and to hold the screen in place. The end cushions 3'' are therefore of greater depth than the cushions 3' on the bottom and top.

Fig. 3 illustrates a modified form particularly suited to certain grades of rubber or cushion materials. In this modification the screen 1 and frame 2 have cushions for the purposes above described, but the material of the cushions 3''' is thickened or reenforced at 5 so as to provide a strong grip on the screen frame 2, while the edges 6 which are designed to extend in the window or other casing are made thinner, so as to provide adequate flexibility even when fairly solid grades of rubber or equivalent material are used.

Any of the forms may have cushions all around as in Fig. 2, or added holes or openings such as 4 to increase flexibility, the forms shown being merely illustrative examples. The invention is characterized by the form of cushioning described which permits easy installation or removal from any ordinary frame, without tools or excessive effort, even when the frame has

warped or swelled; effectively seals irregularities, and permits non-telescoping or unitary screens of stock sizes to fit window openings of various sizes over a reasonable range, as wings have a considerable degree of compressibility.

While I have in the foregoing described particular embodiments of the invention, it will be understood that they are merely for purposes of illustration to make clear the principles thereof, and that the invention is not limited to the particular forms described, but is subject to various modifications and adaptations in different installations as will be apparent to those skilled in the art, without departing from the scope of the invention as stated in the following claims.

I claim:

1. In a screen for sliding windows having window grooves, the combination of a mesh, a frame surrounding the mesh, and resilient cushions on two opposite edges of the frame, said cushions having sufficient body to flex and yield in passing over a window groove edge in installation and removal, and when installed to retain the screen in place by the inherent elastic expansion.

2. In a screen for sliding windows having window grooves, the combination of a mesh, a frame surrounding the mesh, resilient cushions on two opposite edges of the frame, said cushions having sufficient body to flex and yield in passing over a window groove edge in installation and removal, and when installed to retain the screen in place by the inherent elastic expansion, and resilient cushions of less body along the other two opposite edges of the frame, whereby the screen may accommodate itself to irregularities to form an effective seal.

3. In a screen for sliding windows having window grooves, the combination of a mesh, a frame surrounding the mesh, resilient cushions on two opposite edges of the frame, said cushions being of greater thickness than the frame and having sufficient body to flex and yield in passing over a window groove edge in installation and removal, and when installed to retain the screen in place by the inherent elastic expansion.

4. In a screen for sliding windows having window grooves, the combination of a mesh, a frame surrounding the mesh, resilient cushions on two opposite edges of the frame, said cushions being of greater thickness than the frame and having sufficient body to flex and yield in passing

over a window groove edge in installation and removal, and when installed to retain the screen in place by the inherent elastic expansion, and resilient cushions of less body along the other two opposite edges of the frame, whereby the screen may accommodate itself to irregularities to form an effective seal.

5. In a screen for sliding windows having window grooves, the combination of a mesh, a substantially rigid frame surrounding the mesh, resilient cushions on two opposite edges of the frame, said cushions being of greater thickness than the frame and having sufficient body to flex and yield in passing over a window groove edge in installation and removal, and when installed to retain the screen in place by the inherent elastic expansion, the cushions being of a soft and spongy character to provide a broad gripping surface with light pressure, whereby the screen may adjust itself to variable conditions.

6. In a screen for sliding windows having window grooves, the combination of a mesh, a substantially rigid frame surrounding the mesh, resilient cushions on two opposite edges of the frame, said cushions being of greater thickness than the frame and having sufficient body to flex and yield in passing over a window groove edge in installation and removal, and when installed to retain the screen in place by the inherent elastic expansion, the cushions being of a soft and spongy character to provide a broad gripping surface with light unit pressure, and resilient cushions of less body along the other two opposite edges of the frame, whereby the screen may adjust itself to variable conditions.

7. In a unitary screen for sliding windows having window grooves, the combination of a mesh, a frame surrounding the mesh, and resilient cushions of sponge rubber attached to said frame, said cushions having sufficient body to flex and yield in passing over a window groove edge in installation and removal, and when installed to retain the screen in place by the inherent elastic expansion, the cushions being of a soft and spongy character to provide a broad gripping surface with light unit pressure and being porous to air.

RICHARD E. MASON.
